HEATING OF FLUIDS

Filed Oct. 23, 1942

UNITED STATES PATENT OFFICE

2,374,797

HEATING OF FLUIDS

Marion W. Barnes, Chicago, Ill., assignor to Universal Oil Products Company, Chicago, Ill., a corporation of Delaware

Application October 23, 1942, Serial No. 463,056

2 Claims. (Cl. 122—356)

The invention is directed to an improved form of heater of the radiant and convection type which will be found particularly advantageous as applied to heating hydrocarbon vapors, normally gaseous hydrocarbons or other vaporous or gaseous materials to high temperatures. The invention also embraces the improved method of heating which may be conducted in heaters such as herein provided.

Numerous industrial processes, including, for example, operations conducted for effecting the catalytic or thermal conversion of hydrocarbons, involve heating relatively large quantities of gas or vapor to high temperatures, such as, for example, of the order of 800 to 1200° F. In some instances it is necessary to fire heaters employed for this class of service with fuels, such as blast-furnace gas, producer gas, etc., which have a low calorific value and give a relatively low flame-burst temperature as compared with the more preferable fuels, such as natural gas, fuel oil, refinery gases and the like.

It is well known that the use of radiant heat energy from flames and hot combustion gases is practically mandatory to obtain quick heating of hydrocarbon oils, gases and vapors to high reaction temperatures due to the high heat transfer rates required. However, the high heat transfer rates obtainable by radiant heating with fuels of high calorific value cannot be achieved with low grade or diluted fuels due to their low calorific value and low flame-burst temperature. Consequently, the best types of heaters heretofore commonly employed by the refining industry in thermal and catalytic processes, which were designed to operate on fuels of high calorific value to give high radiant heat liberation and employ a relatively high ratio of radiant heating surface to convection surface, are not so successful as applied to the present problems above outlined.

It is the primary object of the present invention to provide an improved form of heater and method of heating which obviate the difficulties above mentioned, permitting the use of relatively low grade fuels and providing high rates of heat transfer from the flames and freshly generated combustion gases which closely approach the maximum rates obtainable with the particular fuel employed.

It is well known that fairly high heat transfer rates can be accomplished by convective heating with flue gas recirculation. However, the rates thus obtainable are not as high as those which can be achieved by direct radiation from flames and nascent hot combustion gases even when em-

ploying fuels of relatively low calorific value. Therefore, in the heater herein provided I employ flue gas recirculation and also employ direct radiation from the flames and nascent hot combustion gases, but limit flue gas recirculation to that section of the heater in which combustion gases which have given up a large portion of their radiant energy are directly contacted with the fluid conduits through which the material undergoing treatment is passed. In another section of the heater, through which no flue gases are recycled, I provide fluid conduits disposed outside the direct path of travel of the flames and freshly generated hot combustion gases and transmit radiant heat directly to these conduits from said flames and hot combustion gases and from refractory surfaces over which the flames and hot combustion gases are passed before being commingled with the recycled flue gas. Thus, the radiant and convection heating sections are maintained separate and rates of heat transmission closely approaching the highest obtainable with the particular type of fuel and type of heating employed, are obtained in each of these sections. The features and advantages of the invention will be more apparent with reference to the accompanying diagrammatic drawing which is an elevational view, shown principally in section, of one specific form of the improved heater provided by the invention.

The heater illustrated in the drawing is of the general type now widely used in the oil refining industry and known as an "equiflux" heater. This type of heater, without the improvements herein provided, is disclosed in U. S. Patent 2,029,293 of J. G. Alther, Patent 2,212,526 of L. A. Mekler and my co-pending application Serial No. 364,832 and numerous other patents and pending applications.

The figure of the drawing shows a vertical section of the heater.

Referring to the drawing, the structure here illustrated is a single cell equiflux heater comprising substantially vertical refractory side walls 1 and 2, refractory end walls, one of which is designated at 3, and a refractory roof 4.

The upper section of the heater comprises combustion and radiant heating zones 5 and 6 between which is disposed equiflux tube bank 7 comprising, in the particular case illustrated, two substantially parallel rows of horizontally disposed tubes 8, although a bank containing a single row of tubes or more than two rows may be substituted, when desired.

The lower section of the heater comprises a fluid heating zone 9 containing a tube bank 10.

which comprises, in this particular instance, a plurality of superimposed horizontal rows of horizontally disposed tubes 11.

The heater is fired through rows of burner ports 12 disposed in the roof 4 adjacent the refractory side walls 1 and 2 by means of burners 13 to which fuel is supplied through lines 14 and valves 15. The burners project flames and nascent hot combustion gases downwardly over the surface of the refractory walls 1 and 2 facing the tubes of bank 7. The surfaces of walls 1 and 2 are heated to a highly radiant condition by the flames and nascent hot combustion gases passing thereover and heat is transmitted from the walls and from said flames and hot combustion gases directly to opposite sides of the tubes of bank 7 through which the fluid undergoing heating is passed in any desired manner. It will be noted from the arrows in combustion zones 5 and 6, which indicate the general path of travel of the flames and hot combustion gases therethrough, that tube bank 7 is disposed outside the direct path of flow of the flames and nascent hot combustion gases and is heated predominantly by radiation.

The combustion gases which have given up all or a major portion of their radiant heat to the tubes of bank 7 pass from combustion zones 5 and 6 through fluid heating zone 9 wherein they wash the tubes of bank 10 and supply fluid heat thereto and to the fluid undergoing treatment which is passed through these tubes. The combustion gases are directed from zone 9 through the combustion gas tunnel or flue 16 leading to a suitable stack, not shown.

In accordance with the provisions of the invention, regulated quantities of the gases discharged from fluid heating zone 9 are directed from flue 16 through duct 17 to a suitable flue gas recirculating fan or blower 18, wherefrom they are supplied through duct 19 and branch ducts 19' and 19'' to the respective chambers 20 and 21. Chambers 20 and 21 are disposed adjacent the lower portions of the respective walls 1 and 2 and communicate through suitable conduits 22 with a zone 33 provided within the heater between the lower extremity of tube bank 7 and the upper extremity of tube bank 10. Recirculated flue gases are directed from chambers 20 and 21 through conduits 22 into zone 33 wherein they commingle with the combustion gases passing from combustion zones 5 and 6 to fluid heating zone 9, thus setting up a cycle of combustion gases, the cycle excluding combustion and radiant heating zones 5 and 6. Thus, dilution of the freshly generated hot combustion gases in zones 5 and 6 is avoided, whereby the rate of radiant heat transmission to the tubes of bank 7 is kept at a value closely approaching the maximum obtainable with the particular type of fuel employed, while a highly increased rate of heating by convection is obtained in bank 10 by flue gas recirculation through zone 9.

The invention also contemplates, when desired, preheating the air utilized to support combustion of the fuel in zones 5 and 6. Although this is not a limiting feature of the invention it is preferably employed when fuel of relatively low calorific value is utilized, in order to increase the flame temperature in zones 5 and 6 and increase the radiant heat transmission to the tubes of bank 7. Preheating of the air is accomplished, in the case illustrated, by admitting it to zones 23 and 24 through the respective conduits 25 and

26 controlled, respectively, by dampers 27 and 28. Zones 23 and 24 are formed, in the case illustrated, as are chambers 20 and 21, between the side walls 1 and 2 and an outer jacket 29 formed of sheet metal or other suitable sheet material and preferably lined with suitable insulating material 30. The jacket 29 extends over the burner ports 12 to enclose burners 13 in zones 31 and 32 and air admitted to zones 23 and 24, as previously described, is preheated by contact with walls 1 and 2 as it passes upwardly thereover and the preheated air is directed, in part, through the burners and, in part, directly through the firing ports 12 into zones 5 and 6.

Any other convenient method and means of preheating the air employed for combustion of the fuel in zones 5 and 6 may be employed within the scope of the invention in conjunction with or in place of the method and means illustrated. For example, I may employ the method and means illustrated in the aforementioned Alther Patent 2,029,293, utilizing any suitable form of air preheater in the combustion gas passageway leading to the stack for recovering heat from the stack gases by indirect contact between the latter and air, the resulting preheated air being supplied through ducts 25 and 26, as previously described, to the combustion zones or directly to the chambers 31 and 32 within which the burners 13 are disposed. Air may be drawn through the preheater and/or through zones 23 and 24 by the inspirator action of the burners or it may be supplied by means of a suitable fan or blower, not illustrated.

I claim as my invention:

1. A heater for fluids comprising a furnace having a radiant heating section and a convection heating section in vertical alignment, said sections being spaced from each other to provide a mixing zone therebetween, a vertical bank of heating tubes disposed within said radiant section and dividing the latter into a pair of combustion zones, means for passing combustion products vertically through each of the combustion zones and from both of the last-named zones into said mixing zone and thence through said convection section, heating tubes in the convection section disposed in the path of travel of the combustion products therethrough, a combustion gas discharge flue communicating with the convection section, and means for introducing to said mixing zone a regulated portion of the combustion gases discharging through said flue.

2. A heater for fluids comprising a furnace having a radiant heating section and a convection heating section in vertical alignment, said sections being spaced from each other to provide a mixing zone therebetween, a vertical bank of heating tubes disposed within said radiant section and dividing the latter into a pair of combustion zones, means for passing combustion products vertically through each of the combustion zones and from both of the last-named zones into said mixing zone and thence through said convection section, heating tubes in the convection section disposed in the path of travel of the combustion products therethrough, a combustion gas discharge flue communicating with the convection section, and means for supplying combustion gases from said flue to said mixing zone on each side of the vertical plane of said tube bank.

MARION W. BARNES.
